INFANT'S GARMENT

Ona Sieloff, Ferndale, Mich.

Application May 18, 1944, Serial No. 536,065

2 Claims. (Cl. 2—75)

1

This invention relates to infant wear and has particular reference to a combined outer and undergarment for infants of tender age.

An object of the invention is to provide a garment in which an infant may be dressed without the necessity of excessive handling of the child.

Another object of the invention is the provision of a garment of the character referred to which is simple in construction, inexpensive to manufacture, and one which is provided with a high degree of esthetic value.

Another object of the invention is the provision of an infant's garment which is easily laundered and which may be ironed flat.

The foregoing objects and other objects and advantages of the invention will appear as the description proceeds, reference being made from time to time to the accompanying drawings forming part of the within disclosure, in which drawings:

Fig. 1 is a front view of a garment embodying the invention.

Fig. 2 is a view similar to Fig. 1 with the front panel of the garment folded back.

Fig. 3 is a plan view of the three panels comprising the garment in outstretched position.

Referring now more particularly to the drawings, it will be understood that in the embodiment herein disclosed, my improved infant's garment consists of a front panel 5, an intermediate panel 6, and a back panel 7, all of which are finished as at 8 and preferably stitched together along the seams 9 and 10.

The front panel 5 may be formed with pleats 11 to provide freedom of movement and for decorative purposes. It will be noted in Fig. 3 that the back panel 7 is formed of two layers of material 1a and 1b, the layer 1a comprising the outer garment and the layer 1b serving as an undergarment. Each of the panels 5, 6, and 7 is provided with cut-out portions 12, 13, and 14 at the top to fit the neck, the cut-out portions 12 and 13 in the front panels being lower than the cut-out portion 14 of the back panel. The panels are also formed with cut-out portions 15, 16, 17, and 18 to provide armholes, there being sleeves 19 and 20 sewed to the panels along the cut-out portions 17 and 18 as shown in Fig. 3.

The garment is provided with a plurality of tie ribbons 21, 22, 23, 24, 25, 26, 27, 28, 29, and 30 which are used as hereinafter described.

In dressing the infant, the garment is spread out as shown in Fig. 3. The infant is then laid,

2

back down, on the panel 7. The infant's left arm is then inserted through the armhole 18 and through the sleeve 20 and the right arm is inserted through the armhole 17 and through the sleeve 19. Panel 6 is then drawn across the child's body and assumes the position shown in Fig. 2. In this position the ribbons 25 and 30 are tied together and the ribbons 24 and 29 are tied together as shown in Fig. 2. The panel 5 is then drawn across the panel 6 (Fig. 2) and the ribbon 22 is tied to the ribbon 27 and the ribbon 23 is tied to the ribbon 26, making decorative bows on the left shoulder as shown in Fig. 1. The ribbon 21 is then tied to the ribbon 28, making a decorative bow under the left sleeve as shown in Fig. 1. The device is now completely assembled to form an outer and inner garment both in front and back.

Having described my invention, what I claim and desire to secure by Letters Patent is:

1. In a device of the character described, the combination of a central panel having a double thickness of material open at the bottom and adapted to serve as respective sections of an outer skirt and an under skirt, a wing panel on either side of said central panel, one of said wing panels being arranged to fold completely over said central panel to form another section of the under skirt, and the other said wing panel being arranged to fold over said first-named wing panel to form another section of said outer skirt, and means to secure said panels in predetermined position.

2. A child's garment comprising a length of material, having a central section of double thickness, and folded and refolded upon itself to provide outer and inner skirt sections, arm cut-out portions, and tie members positioned adjacent to said arm cut-out portions, whereby said folds may be secured in predetermined position.

ONA SIELOFF.
